CHILD'S ROCKING CHAIR

Donald G. Locke, 27802 Park Court,
Madison Heights, Mich.

Filed Feb. 11, 1959, Ser. No. 54,551

Term of patent 14 years

(Cl. D15—6)

Fig. 3

Fig. 2

Fig. 1

Fig. 1 is a front perspective view of a child's rocking chair showing my design;

Fig. 2 is a side elevational view; and

Fig. 3 is a front elevational view thereof.

The side of the chair not shown is the same in appearance as the side shown while the back of the chair is conventional in that it terminates adjacent the top edge of the seat and its rear face has an appearance similar to its front face.

The dominant features of my design constitute a substantially swan-shaped representation including a lower rear end portion merging smoothly with a rocker bottom which in turn smoothly merges at its forward end in a neck portion that is upwardly arched and reversely curved intermediate its ends to provide an intermediate neck portion resting on the upper body and having a terminal neck portion resting on an intermediate neck portion,

the reversely curved portion of said neck providing a pair of spaced apart openings between the body portion and the terminal end portion, respectively.

I claim:

The ornamental design for a child's rocking chair, as shown and described.
